(57) CLAIM

The ornamental design for a battery for a vaporizer, as shown and described.

DESCRIPTION

FIG. 1 is a front perspective view of a battery for a vaporizer, shown in an environment of use.

FIG. 2 is a front view of the battery for a vaporizer of FIG. 1;

FIG. 3 is a side view of the battery for a vaporizer of FIG. 1;

FIG. 4 is a rear view of the battery for a vaporizer of FIG. 1;

FIG. 5 is a top view of the battery for a vaporizer of FIG. 1; and,

FIG. 6 is a bottom view of the battery for a vaporizer of FIG. 1.

The broken lines shown in the drawings are included for the purpose of illustrating environmental structure and form no part of the claimed design.
